DOOR CHECK

Robert S. Heron, Brooklyn, Ohio, assignor, by mesne assignments, to Lisle W. Menzimer, Rockford, Ill., trustee

Application March 14, 1956, Serial No. 571,547

10 Claims. (Cl. 16—82)

This invention relates to door checks, and more particularly to door checks of the kind which will hold a door in different desired positions.

There exists a definite need for a satisfactory door check of this kind, particularly for the rear doors of delivery trucks of the panel body type. In such delivery trucks it is desirable that the door check be capable of holding a rear door at either a substantially 180° full open position or at a substantially 90° partially open position. The hinge arrangement and balance for such a rear door are usually such that when the door is on one side of the 90° position it will tend to fall shut, and when the door is at, or on the other side of the 90° position, it will tend to fall toward the full open or 180° position.

It is desirable that the door be openable to the 180° position so as to permit the rear end of the truck to be moved up close to a loading dock or platform without interference from the door. On the other hand, when the truck is standing at a curb or in a roadside position and the rear doors are opened, one of those doors, usually the left-hand door, if opened to its 180° position, will extend into the adjacent traffic lane and will create a hazard. It is, therefore, necessary that the door check be capable of holding the door at the 90° open position so that the door will not extend into the adjacent traffic lane.

The present invention, accordingly, has, as one of its objects, the provision of a novel door check which will hold a door in different desired open positions, and which is of a relatively simple and practical form capable of being readily manufactured and installed.

Another object is to provide such a door check which will automatically assume an engaged condition for holding the door in an intermediate open position, such as a 90° position, and in which the engaged condition is releasable for movement of the door to another predetermined open position or to its closed position.

Still another object is to provide a novel multiple door-position door check comprising an extensible articulated linkage which includes a pair of pivoted link members having their adjacent end portions in a coextending relation and carrying cooperating elements for establishing the different door-holding settings, and in which confining means associated with the link members confines the same substantially to their coextending relation during the extension and contraction of the linkage throughout the full range of door movements, the cooperating elements being engageable and releasable by a limited relative movement between the link members in a direction transversely of the linkage.

Additionally, this invention provides such a multiple-position door check in which means effective on at least one of the link members, preferably a friction means incorporated in one of the pivots tends to produce a relative movement between the link members transversely of the linkage for causing engagement of the cooperating elements, in response to relative longitudinal movement between the link members.

Other objects and advantages of the invention will be

2

apparent in the following detailed description and in the accompanying sheets of drawings forming a part of this specification, and in which:

Fig. 1 is a partial rear end elevation of a vehicle having swingable doors equipped with door checks embodying the present invention;

Fig. 2 is a partial transverse horizontal section on a somewhat larger scale taken through the vehicle, as indicated by section line 2—2 of Fig. 1 and showing the closed position of the left-hand door and the corresponding collapsed condition of its associated door check;

Fig. 3 is a partial transverse horizontal section similar to Fig. 2 but showing the door in its full-open position and the corresponding extended condition of its associated door check;

Fig. 4 is a partial vertical longitudinal section taken through the door check as indicated by section line 4—4 of Fig. 3;

Fig. 5 is a partial vertical section on a somewhat larger scale and taken through one of the pivotal connections of the door check, as indicated by section line 5—5 of Figs. 1 and 2;

Fig. 6 is a transverse vertical section taken on line 6—6 of Fig. 2; and

Fig. 7 is an end elevation of the door check when viewed as indicated by the directional line 7—7 of Fig. 2.

By way of example, the drawings show the novel door check of the present invention applied to a delivery truck 10 of the panel body type having a doorway 11 in the rear end thereof and a pair of rear doors 12 and 13 for closing such doorway. Door checks 14 and 15 of the novel construction provided by this invention are applied to the doors 12 and 13 for holding the same in the desired full open, or partially open, positions in the manner to be explained hereinafter. The door checks 14 and 15 are identical in construction, with the exception that they are for right-hand and left-hand installation to suit the right-hand and left-hand doors 12 and 13 to which they are applied.

The doorway 11 of the truck 10 is defined by body portions constituting the door frame structure which includes upright side edge or pillar portions 16 and 17 and a transverse top portion or lintel 18. The doors 12 and 13 are swingably mounted on the upright doorframe portions 16 and 17 by pairs of suitable hinges 19 which are attached to these doorframe portions and to the adjacent upright edge portions 20 and 21 of the doors. When the doors are in their closed position, as shown in Fig. 1, their free edges 22 and 23 are in a meeting or engaged relation in or adjacent a common parting plane, and in this instance, the edge portion of the left-hand door 13 is provided with a stop flange 25 with which the edge portion of the right-hand door 12 has an abutting engagement in an overlapping relation thereto, as shown in Fig. 2.

The right-hand door 12 is here shown as provided with a suitable handle 26 for swinging the same and, if desired, a similar handle can be provided on the door 13. The doors 12 and 13 also include an upper edge wall 28 which is located adjacent to but below the transverse doorframe portion 18 when the doors are in their closed position.

For a more detailed description of the invention, reference need be made only to the left-hand door 13 and to the door check 15 associated therewith. As shown in Fig. 3, the door 13 is swingable from a closed position 13^a to intermediate and full-open positions 13^b and 13^c. The intermediate position 13^b is a substantially 90° position and the position 13^c is a substantially 180° open position.

The location of the hinges 19 is such that if the door 13 is in its 90° position 13^b and is then released, it will tend to fall open toward its 180° position 13^c, and if the

door is somewhat to the right of the 90° position 13^b when it is released, it will tend to fall shut. As will be explained more fully hereinafter, the door check 15 has an engaged condition providing an intermediate door-holding length for holding the door 13 in the 90° position 13^b and also has a second engaged condition, which in this case is its fully extended length, for holding the door in the 180° position 13^c.

The door check 15 is in the form of an extensible articulated linkage which comprises, in general, a pair of attaching members 29 and 30 for connecting the opposite ends of the linkage with the door and doorframe structures respectively, and a linkage unit 31 extending between the attaching members and comprising a pair of link members 32 and 33 having their adjacent ends in an overlapping or telescoping relation. The door check 15 also comprises cooperating guideway and guide follower elements carried by the link members, the guideway being here shown in the form of a longitudinal slot 34 in the link member 32 and the follower being here shown as a pin 35 carried by the link member 33 and movable along such slot. As shown in Figs. 2 and 3 the slot 34 extends along the link member 32 for a major portion of the length of the latter.

The attaching member 29 can be of any appropriate form and is here shown as comprising a substantially flat plate bracket adapted to be secured to the top edge wall 28 of the door 13 by the connecting screws 36. The bracket 29 carries a headed pivot member 38 by which the outer end 39 of the link member 32 is pivotally attached to this bracket.

The attaching member 30 can also be a bracket made of sheet metal or plate material and is here shown as being of a substantially L-shaped form having substantially right-angularly disposed flat upright and horizontal legs 40 and 41. The bracket 30 can be mounted on the doorframe member 18 with the flat upright leg 40 secured thereagainst by the connecting screws 42. The horizontal leg 41 carries a pivot pin 43 by which the outer end 44 of the link member 33 is pivotally connected with this bracket.

The link member 32 can be a substantially straight bar of an appropriate length and is here shown as being a sheet metal member of a channel-shaped cross-section having a substantially flat longitudinal web portion 47 and substantially parallel longitudinal edge flanges 48 and 49. The slot 34 extends along the link member 32 for a substantial portion of its length and is suitably formed in the web portion 47 of this member.

The slot 34 has longitudinally extending side edges 50 and 51 along opposite sides thereof and one of those side edges, in this instance the side edge 51, has a laterally offset portion forming an abutment shoulder or stop 52. The stop 52 is engageable by the follower pin 35 for holding the door 13 in its intermediate or 90° position 13^b, as explained hereinafter, and can be located at any appropriate point along the side edge 51 of the slot 34, depending upon the position in which the door is desired to be held. The stop 52 is here shown as being located adjacent the midpoint of this side edge of the slot. Adjacent the stop 52, the slot 34 has a relatively wide tapered portion 54, such that the abutment shoulder forming this stop faces toward the pivot 38 and is engageable by the pin 35 when the latter is moving along the slot in a direction away from the pivot 38.

The link member 32 is provided with a second stop 55 which is engageable by the pin 35 for holding the door 13 in its full open or 180° position 13^c. This second stop is here shown as being formed by the end of the slot 34 which is remote from the pivot 38.

The link member 33 can also be a substantially straight sheet metal member having a substantially flat longitudinal arm or web portion 57 which is in a substantially parallel relation to the web portion 47 of the

link member 32. The link member 33 has a longitudinal flange 58 thereon, which is here shown as being an edge flange formed on the end portion 59 of this link member which is overlapped by the adjacent end portion of the link member 32. As shown in the drawings, the pin 35 is mounted on the link member 31 so as to be spaced from the edge flange 58 thereof a distance such that this pin will be located directly opposite and for movement into, the open end of the narrow portion of the slot 34 when the flange 58 is in engagement with the flange 49 of the link member 32.

The link members 32 and 33 are preferably disposed with the flanged sides thereof facing each other. The flanged end portion 59 of the link member 33 is wider than the link member 32 so as to extend across and beyond the edge flanges 48 and 49 of the latter, as shown in Fig. 2. The link members 32 and 33 extend in a substantially longitudinally aligned relation with one of the edge flanges of the link member 32, in this instance the edge flange 49, lying adjacent to and slidable along the flange 58 of the link member 33.

The guide follower pin 35 is mounted in a fixed relation on the wide end portion 59 of the link member 33 substantially on the longitudinal center line thereof and can be in the form of a pin whose stem portion 60 is disposed in the slot 34 and whose reduced end 61 is secured in shouldered engagement with the web 57 by the riveted portion 62. The pin 35 is provided with a disk-like head 63 and with a disk-shaped washer 64 disposed on the stem 60 adjacent the head and spanning the slot 34. The pin 35 thus serves as a connecting means for the overlapping portions of the link members 32 and 33 as well as a guide follower movable along the slot 34.

The proportions and dimensions of the link members 32 and 33 and the locations of the brackets 29 and 30, are such that when the stem 60 of the follower pin 35 is engaged by the stop 52 of the link member 32, as shown in broken lines in Fig. 3, the door 13 will be retained in its partially open position 13^b by reason of the fact that the stop 52 is being pulled against the pin 35 by the weight of the door and the tendency of the latter to fall open. When the door 13 is swung to its full open position 13^c, the stop 55 formed by the end of the slot 34 will engage the stem 60 of the follower pin 35, as shown in Fig. 3 and the door will thereupon be held against further opening movement and the opening tendency of the door will maintain the stop 55 in engagement with the pin 35.

When the door 13 is in its closed position 13^a, the linkage unit 31 is in a relatively collapsed condition in which the link members 32 and 33 are coextending for a greater portion of their length, as shown in Fig. 2 of the drawings. At this time the follower pin 35 is located in the end portion of the slot 34 which extends toward the pivot 38. As the door 13 is swung open, the link member 32 moves with the door by reason of a pulling force being applied to this link member through the pivot 38 such that this link member is withdrawn from, or extended relative to, the link member 33. During this relative extending movement of the link member 32, the follower pin 35 moves along the slot 34 into engagement with the stop 52 to establish the above-explained intermediate or 90° door position 13^b.

The relatively wide portion 54 of the slot 34 permits a relative movement between the link members 32 and 33 transversely of the linkage for disengagement of the follower pin 35 from the stop 52. This relative transverse movement between the link members 32 and 33 can be produced by a manual force applied to one or both of these link members, such as a manual force applied to the linkage with the thumb and fingers of the same hand engaging opposite sides of the linkage and squeezing the link members toward each other, to thereby

displace the follower pin 35 from the stop 52 and toward the straight side edge 50 of the slot. When the follower pin 35 has been thus disengaged from the stop 52, it is free to move along the slot 34 toward the end stop 55 thereof. This freedom of movement of the follower pin 35 permits further extension of the link member 32 relative to the link member 33 during which the door 13 is being swung from the 90° position 13^b to the full-open or 180° position 13^c.

When the follower pin 35 is in engagement with the stop 52, the edge flange 49 of the link member 32 and the flange 58 of the link member 33 are in a relatively spaced-apart relation, as shown in Fig. 3, such that the above-described relative transverse movement between the link members can readily take place upon the application of the manual squeezing force to the linkage.

It is desirable that the pin 35 move into the wide slot portion 54 during each opening movement of the door 13 so as to automatically engage the stop 52 when the door arrives at its 90° open position 13^b. For this purpose the door check 15 is provided with means for producing a drag effect on one of the link members, in this instance the link member 33. This drag effect is produced, in accordance with the present invention, by incorporating frictional resistance in the pivot 43 in a manner which will now be described.

The pivot 43 can be in the form of a pin 66 having a reduced stem portion 67 riveted to the plate portion 41 of the bracket 30 and also having a stem portion 68 extending through an opening 69 of the link member 33. A disk-shaped washer 70 of a bowed form is disposed around the stem portion 68 and is confined by the head 71 of the latter so as to apply a clamping pressure against the link member 33 for pressing the same in a face-to-face engagement with the plate portion 41 of the bracket 30. The washer 70 is preferably a spring steel washer, which is maintained under a loaded condition by the assembled relation of the pivot member 43 with the bracket 30.

By reason of the frictional drag produced by the action of the washer 70, the tendency of the link member 33 will be to resist swinging thereof in a counterclockwise direction, as seen in Figs. 2 and 3, by the link member 32 such that during the opening movement of the door 13, the follower pin 35 will hug the side edge 51 of the slot 34 and will move into the wide slot portion 54 and engage the stop 52, as explained above, during each opening movement of the door.

From the construction and operation of the door check 15 as above described it will be understood that the manual release of the pin 35 from the stop 52 is only necessary when the door 13 is to be swung from its 90° position to its full 180° position. When the door is being swung shut from either its 90° position or its 180° position, the pin 35 has a free movement along the slot 34 during which it hugs the straight side edge 50 by reason of the frictional drag resisting clockwise swinging of the link member 32 on the pivot 43.

When the door 13 is being swung shut from its 90° position, the pin 35 simply moves away from the stop 52 by moving along the slot 34 toward the pivot 38. Likewise, when the door is being swung shut from its 180° position, the pin 35 moves away from the stop 55 and along the slot 34 toward the pivot 38 and, since the pin at this time is moving in the same direction as the stop 52 faces, the pin moves freely past the stop without engaging the same. The closing of the door from its full-open position thus takes place as a continuous and uninterrupted swinging movement.

Since the attaching bracket 29 is mounted on the door 13 at a point adjacent the axis of the hingers 19 and the bracket 30 is mounted on the doorframe 18 at a point spaced a substantial distance from the hinge axis, it will be seen that as the door swings from its full-open

position to its closed position, the link members 32 and 33 will always remain in a substantially longitudinally aligned relation with the amount of overlap between the link members varying with the different positions assumed by the door. The maintaining of this substantially aligned relation of the link members gives the linkage unit 31 its rigidity and ability to hold the door in the desired different positions. This aligned relation of the link members 32 and 33 results from the confining action of the co-operating flanges 49 and 58 of these members, by which the relative movement between the link members in a direction transversely of the linkage is confined to merely the amount of movement therebetween needed to disengage the follower pin 35 from the stop 52.

From the accompanying drawings and the foregoing detailed description, it will accordingly be understood that this invention provides a relatively simple and practical form of door check which can be readily manufactured and easily installed. It will now also be understood that this door check will effectively hold a door in different desired open positions and that the door-holding action for the intermediate position can be readily released by manual manipulation of the cooperating link members.

Although the door check of the present invention has been illustrated and described herein to a somewhat detailed extent, it will be understood, of course, that the invention is not to be regarded as being limited correspondingly in scope since it is intended to include all changes and modifications coming within the terms of the claims hereof.

Having thus described my invention, I claim:

1. A door check comprising an extensible articulated linkage including a pair of link members extending in substantially the same direction with adjacent end portions 35 of the link members in overlapping relation, attaching devices pivotally connected with the remote ends of said link members and adapted for attachment to a door and its associated door frame, means connecting said link members for relative movement therebetween comprising 40 guide means on one link member and extending therewith and guide follower means mounted in a fixed relation on the other link member, stop elements on said one link member and located adjacent said guide means and at spaced points along the latter, said stop elements 45 facing in the same direction along said guide means and being selectively engageable by said follower means for establishing different door-positioning lengths for said linkage for checking movement of said door in a given direction at different points of such door movement, said guide and guide follower means having limited relative movement in a direction transversely of the linkage for engaging said follower means with and disengaging said follower means from one of said stop elements, and means effective on said link members for confining the same to a substantially longitudinally aligned relation during their relative longitudinal movements produced during movement of the door between its closed position and its full open position.

2. A door check as defined in claim 1 in which said last named means also limits the extent of the transverse movement between said link members and comprising a confining element extending along at least one of the link members and engaged by a portion of the other link member.

3. A multiple door-position door check for use between a support and a door hinged thereto comprising, a first attaching means adapted for connection with said door, a second attaching means adapted for connection with said support at a point spaced from the hinge axis, an intermediate linkage unit extending between and having its ends pivotally connected with said first and second attaching means, said linkage unit comprising a pair of link members one of which has a guideway extending longitudinally thereof, a plurality of stops associated with said guideway including an end stop located at an end

of said guideway and an intermediate stop located at an intermediate point of the length of said guideway and spaced from said end stop said stops facing in the same direction longitudinally of said guideway, and a follower fixedly mounted on and carried by the other link member and movable along said guideway and selectively engageable with said stops for establishing different door-holding lengths for said door check for checking movement of said door in a given direction at different points of such door movement, said link members being in a substantially longitudinally aligned and at least partially coextending relation and having a limited relative movement transversely of said unit for the engagement and disengagement of said follower and intermediate stop, said guideway having a portion providing increased width adjacent said intermediate stop and said follower being shiftable in the guideway portion of increased width during the transverse relative movement of said link members.

4. A door check comprising an extensible articulated linkage having attaching members at the ends thereof for application to associated door and doorframe members and including an intermediate linkage unit extending between and pivotally connected with said attaching members, said linkage unit comprising a pair of longitudinally disposed and at least partially coextending link members one of which has a longitudinal slot and a stop adjacent one side edge of said slot and the other of said link members having a projection fixed thereon and movable along said slot, said projection being engageable with said stop for establishing a given door-holding length for said linkage unit, means effective on one of said link members through the pivotal connection thereof with its associated attaching member for causing said projection to hug said one side edge during relative longitudinal movement in one direction between said link members and to hug the other side edge of said slot during relative longitudinal movement in the opposite direction between said link members, and means for confining the relative longitudinal movement between said link members substantially to a relative movement in the longitudinal direction of and along said unit, said link members having a limited relative movement transversely of said unit for engagement and disengagement of said projection from said stop.

5. A multiple door-position door check for use between a support and a door hinged thereto comprising, a first attaching means adapted for connection with said door, a second attaching means adapted for connection with said support at a point spaced from the hinge axis, an intermediate linkage unit extending between said first and second attaching means, first and second pivots pivotally connecting the ends of said linkage unit with said first and second attaching means, said linkage unit comprising a pair of link members one of which has a guideway extending longitudinally thereof, a plurality of stops associated with said guideway including an end stop located at an end of said guideway and an intermediate stop spaced from said end stop, a follower carried by the other link member and movable along said guideway and selectively engageable with said stops for establishing different door-holding lengths for said linkage unit, said link members being in a substantially longitudinally aligned and at least partially coextending relation and having a limited relative movement transversely of said unit for the engagement and disengagement of said follower and intermediate stop, and friction producing means associated with one of said pivots to retard swinging of the associated link member on said one pivot for causing such transverse relative movement between said link members in response to relative longitudinal movement therebetween and in a direction for causing engagement between said follower and said intermediate stop.

6. A multiple door-position door check for use between a support and a door hinged thereto comprising, a

first attaching means adapted for connection with said door and including a first pivot, a second attaching means adapted for connection with said support at a point spaced from the hinge axis and including a second pivot, an intermediate linkage unit extending between and having its ends pivotally connected with said first and second attaching means by said first and second pivots, said linkage unit comprising a pair of link members one of which has a longitudinal slot therein, a plurality of stops associated with said slot and including an end stop formed by an end of said slot and an intermediate stop located at an intermediate point of the length of said slot and spaced from said end stop, said stops facing in the same direction longitudinally of said slot, and a projection carried by the other link member and movable along said slot and selectively engageable with said stops for establishing different door-holding lengths for said linkage unit, said link members being in a substantially longitudinally aligned and at least partially co-extending relation during movement of the door between its closed and full open positions and having a limited relative movement transversely of said unit for the engagement and disengagement of said projection and intermediate stop, one of said pivots having a friction producing means therein tending to retard swinging of the associated link member on said one pivot to cause engagement between said projection and intermediate stop during relative longitudinal movement between said link members.

7. A door check as defined in claim 6 in which said friction producing means is in the pivot of said second attaching means and comprises a spring washer of bowed form embodied therein.

8. A door check as defined in claim 6 in which the link member containing said slot is of a channel form having longitudinal edge flanges and the other link member has a longitudinal edge portion thereof lying adjacent and slidably along one of said edge flanges.

9. A door check comprising, a pair of link members at least one of which has a substantially flat longitudinal wall portion provided with a guide slot extending longitudinally therewith for a major portion of the length of said one link member and the other of which has an end portion thereof overlapping said flat wall portion for at least a portion of the length of the latter, said link members being disposed with the outer ends thereof extending in generally opposite directions away from the overlapped portions, attaching devices adapted for attachment to a pair of associated door and doorframe members, first and second pivots connecting the outer ends of said link members to said attaching devices, said slot having an intermediate portion of increased width extending along the slot for a portion of its length, a stop on said one link member and located in said slot at an intermediate point of the length of the slot and at one end of said portion of increased width, a follower fixed on said overlapping end portion of said other link member and movable in said slot longitudinally of the latter during relative endwise movements between said link members, confining portions on said link members and co-operably effective for maintaining the link members in a longitudinally extending relation to each other during the full extent of the permissible endwise relative movement between said link members, said follower being confined in said slot during all portions of the relative movement between said follower and slot and said follower being engageable with said stop for establishing a predetermined holding length for the door check, said link members having a limited relative movement in a direction transversely of said slot while said follower is in said slot portion of increased width for causing the follower to engage and disengage said stop, and friction producing means in one of said pivots for retarding swinging movement of one of said link members relative to its associated attaching device to cause an automatic engagement of said follower with said stop in response to

an extending endwise relative movement between said link members.

10. A door check for checking door opening movement comprising, a pair of link members at least one of which has a substantially flat longitudinal wall portion provided with a guide slot extending longitudinally therealong for a major portion of the length of said one link member and the other of which has an end portion thereof overlapping said flat wall portion for at least a portion of the length of the latter, said link members being disposed with the outer ends thereof extending in generally opposite directions away from the overlapped portions, attaching devices connected with said outer ends and adapted for attachment to a pair of associated door and doorframe members, said slot having an intermediate portion of increased width extending along the slot for a portion of its length, a stop on said one link member and located in said slot at an intermediate point of the length of the slot and at one end of said portion of increased width, a follower fixed on said overlapping end portion of said other link member and movable in said slot longitudinally of the latter during relative endwise movements between said link members, and co-operably effective confining portions on said link members for maintaining the link members in a longitudinally extending relation to each other during the full extent of the permissible endwise relative movement between said link members, said follower being confined in said slot during

5 all portions of the relative movement between said follower and slot and said follower being engageable with said stop for establishing a predetermined holding length for checking the opening movement of said door, said link members having a limited relative movement in a direction transversely of said slot while said follower is in said slot portion of increased width for causing the follower to engage and disengage said stop, said one link member being a channel-shaped member comprising a pair of spaced longitudinal side flanges connected by a longitudinal web portion which provides said flat wall portion, said overlapping end portion of said other link member being a second substantially flat wall portion lying in a plane parallel to the plane of said web portion and being of greater transverse width than the transverse spacing of said flanges.
